RADIO APPARATUS

Merion J. Huggins, Upper Saddle River, N. J.

Application May 13, 1933, Serial No. 670,894
Renewed May 8, 1937

23 Claims. (Cl. 250—20)

This invention relates to radio tuning or frequency synchronizing means for radio apparatus, and particularly to means to effect the actuation of variable condensers or other frequency synchronizing apparatus to synchronize or tune the circuits of radio receiving apparatus to resonance with any of a plurality of incoming transmitted radio frequencies at and for intervals or periods of time.

10 It is an object of the invention to provide manually preselected time controlled means to actuate and stop and fasten the tuning means in a multiplicity of selectively predetermined manually preselected positions to tune in the predetermined preselected transmitted frequencies at and for periods of time.

15 It is an object of the invention to provide means to selectively predetermine and change any one or more of the transmitted frequencies 20 to be manually preselected and time controlled to any other transmitted frequency.

25 It is an object to provide means connected in circuit with the tuning actuating means and co-acting with the tuning means whereby said tuning means is actuated and stopped and fastened at predetermined manually preselected intervals or periods of time to tune or synchronize the electric circuits of the radio receiving apparatus to resonance with selectively predetermined manually preselected transmitted frequencies at and 30 for periods of time.

35 It is an object of the invention to provide a type of variable condenser or capacity which is rotated and simultaneously longitudinally reciprocated to and stopped and fastened in a multiplicity of circuit synchronizing positions and thereby spread such detained synchronizing tuning positions over a wide range equalling several hundred degrees or a range exceeding a 40 complete circle.

45 It is an object of the invention to provide time synchronized circuit closing means wherein the circuits are finally closed by a minute actuated member electrically connected to an hour actuated member and wherein means is provided for momentarily delaying the closing of the circuit by the minute actuated member.

50 It is an object of the invention to provide means to place the radio receiver in and out of operative condition, as for instance, by closing and opening the electric supply circuit thereto, at and for manually preselected intervals or periods of time.

55 It is an object of the invention to provide manually operable circuit closing means to effect ac-

tuation of the means to tune or synchronize the circuits to resonance with transmitted frequencies and to turn the receiver on or off, both independent of the manual preselecting and time controlling means.

5 It is an object of the invention to provide means co-acting with the tuning means to control and adjust the audio frequency current output or the audio volume or sound level of each manually preselected time controlled synchronized frequency.

10 In the drawings accompanying and forming a part of this application, Figure 1 is a view showing in elevation, and partly in section, an embodiment of the component parts of the invention and showing diagrammatically the electrical connections thereof.

15 Figure 2 is a sectional view taken on the line 2—2 of Figure 1 looking in the direction of the arrows and showing a modification of the means 20 for selectively determining and changing the tuning positions of the tuning elements and the transmitted frequencies to be manually preselected and time controlled.

25 Figure 3 is a sectional view taken on the line 2—2 of Figure 1 looking in the direction of the arrows.

30 Figures 4 and 5 are end elevations of condenser elements embodied in the present invention.

35 In carrying out the embodiment of the invention illustrated in the drawings, there is provided a suitable type of electric motor 1 with a drive gear 2 on the motor shaft meshing with a driven gear 3 mounted to rotate shaft 4 which is supported by pillars a—b—c—d. Gear 3 is splined to shaft 4 so the shaft may slide or have longitudinal movement therethrough. An adjustable electrode tuning element 5 of a non-conventional type of variable condenser or capacity is fixed 40 to shaft 4 and adapted to have imparted thereto simultaneous rotative and reciprocatory axial movement and thus co-act with a similar stationary electrode tuning element 6 fixedly supported by support 6c, and these two elements 5 45 and 6 interposed in the radio receiving circuit of the radio apparatus, constitute the frequency tuning means.

50 The tuning elements 5 and 6 are in the form of cup members, each member consisting of a disk having a plurality of concentrically arranged and spaced annular plates 5a and 6a projecting from a face of the disk, and the elements arranged with the plates of one element in opposed relation to the spaces between the plates of the 55

other element so that when the adjustable element is axially adjusted the plates thereof will be interengaged with the plates of the fixed element through the rotation and axial movement of shaft 4 and element 5, and thus effect through

5 capacity change the synchronizing or tuning of the radio receiving circuits to resonance with the radio frequencies.

10 The hub of movable element 5 is formed as a bevel gear 5b which is in constant mesh with a suitable ratio co-acting bevel gear 7 eccentrically pivoted at 7a and independently supported by the bracket arm 7b extended from the shaft supporting pillar c.

15 The rotation of shaft 4 in either direction imparts a like rotation of movable element 5 and through gear 5b a proportional eccentric rotation of gear 7 which imparts axial movement to tuning element 5, and there is thus simultaneously imparted proportional rotative and axial movement to element 5 and to shaft 4 against the tension of expansion spring 8 disposed under compression between fixed collar 8a and pillar b which spring yieldingly urges shaft 4 and element 5 and the gear 5a longitudinally against gear 7 thus maintaining gears 5b and 7 in mesh and the tuning elements 5—6 in the relative position shown in the drawings.

20 Accordingly, if the ratio of gears 5b and 7 are 1 to 2, when the gear 3, shaft 4 and element 5 have been rotated one revolution the eccentrically pivoted gear 7 will have rotated one-half revolution and will have simultaneously imparted the maximum axial movement to element 5 to the left as viewed in the drawing. In other words, by each complete revolution of gear 3 and shaft 4 the element 5 will have been rotatably and longitudinally moved to the left as viewed in the drawing and against the yielding spring 8 sufficiently to effect a complete intermeshing of its plates 5a with the plates 6a of the fixed electrode 6. If the rotation of gear 3, shaft 4 and element 5 is continued or reversed another complete revolution gear 7 will rotate another half revolution and through the co-action of spring 8 and gear 7 impart a simultaneous proportional axial movement to the right as viewed in the drawing sufficient to again completely move the plates 5a and 6a out of interengaged relation and return the tuning elements to the position shown in the drawing.

25 Thus if the ratio of gears 5b and 7 is 1 to 2, each complete revolution of gear 3 and shaft 4 will impart rotative and axial movement to the movable element 5 and effect the complete intermeshing and un-meshing of the plates of the tuning elements 5 and 6, and the tuning of the radio frequency circuits by this combined rotative and axial movement in the adjustment of the 30 tuning elements to a plurality of stable tuning positions is thus spread out over some 360 degrees rather than over a radius of some 180 degrees as with all conventional types of tuning condensers, and thus if the gear 3 has 360 teeth the tuning elements can be positioned in any one of 360 tuning positions. Also, if the ratio of gears 5b and 7 is 1 to 4 it will require two revolutions of gear 3, shaft 4 and movable element 5 to effect a complete intermeshing or un-meshing of the 35 plates 5a—6a of the elements 5—6, and if the gear 3 has a relative number of teeth the tuning elements can be positioned in any of 720 tuning positions. By thus providing for the spreading out of the tuning positions the detaining means will more accurately detain the tuning

means in the correct synchronizing position and greatly increase the number of broadcast frequencies which can be synchronized and accurately detained.

40 It will be apparent that instead of fixing movable element 5 to shaft 4 and moving or reciprocating the shaft longitudinally, shaft 4 could be fixed and element 5 movable longitudinally thereof by splining element 5 to shaft 4, and under this arrangement element 5 is rotated with shaft 4 and the eccentrically pivoted gear 7 would impart proportional reciprocal axial movement to element 5 only against a spring 8, but such an arrangement would require an eccentrically pivoted gear for each movable element 5, and where a gang of condensers are used it appears more expedient to fix all movable elements to the shaft for rotative movement and utilize one eccentrically pivoted gear to impart the reciprocatory axial movement to the shaft 20 and therethrough to the movable elements.

45 To arrest and fasten the motor 1 and adjustable tuning element with its blades in adjusted positions for periods of time in any of a multiplicity of intermeshed circuit synchronizing positions with the blades of element 6, or in any of a multiplicity of stable selectively predetermined manually preselected time controlled frequency tuning positions, there is provided a latch bar 9 pivoted at 9a and yieldingly urged by a spring 9b into engagement, for intervals of time, with any one of the multiplicity of tooth notches of a toothed wheel, in the present instance the driven gear 3, and this latch bar 9 is adapted to be disengaged and retained out of engagement with any one of said tooth notches, for short intervals of time, by the electric energization of an electromagnet 10, and the latch bar 9 is further adapted to simultaneously make electrical contact with a contact member 11 and thereby close the electrical circuit to and through the actuating motor 1 for like short intervals or periods of time.

50 To selectively determine and automatically effect the arrest and fastening of the motor and the corresponding and correct interengaging of the plates of element 5 with the plates of element 6 to effect different frequency synchronizing positions, and the fastening thereof in any of a multiplicity of such correct circuit synchronizing positions to synchronize the radio receiving circuits to resonance with any one of a plurality of broadcast frequencies for intervals or periods of time, and to coordinate the electrical energization of motor 1 and latch bar 55 magnet 10, there is provided adjustable frequency selecting and changing means, comprising a cylinder 12 of conducting material having a non-conducting space, herein shown as a member 16 of dielectric material inserted in the peripheral 60 wall of and extending longitudinally of the cylinder 12, and a plurality of adjustably mounted metal contact makers, two of which contact makers 14, 15 are shown, said contact makers being adjustably stepped about the cylinder 12 65 so they are arranged to contact with the cylinder 12 and close an electric circuit through one of said contact makers and the cylinder and at predetermined points in the rotation of co-ordinated movement of the cylinder contact with the single 70 non-conducting space arranged in the periphery of the cylinder and break the electrical contact of each of said contact makers with the cylinder 12. An electric conductor brush 13 mounted on a dielectric support 13a is in constant contact 75

and electric connection with the cylinder. The cylinder 12 is insulated from and splined to the shaft 4, or otherwise arranged to have movement imparted thereto in co-ordinated unison with the motor or driven gear 3, adjustable element 5 and gear 1.

Each of the brushes 14 and 15 is mounted on an independent and selectively adjustable annular supports 17 and 18 of dielectric material, 10 so that each contact brush can be independently and selectively adjusted around the periphery of the metal cylinder 12 and relative to a single circuit breaking element or non-conducting space, and shown as a dielectric insert 16 to a 15 position relatively corresponding to any one of the tooth spaces in driven gear 3, which adjustment also selectively predetermines the opening of the motor circuit and the arresting and fastening, for a period of time, of the tuning element 5 in any one of a multiplicity of circuit synchronizing resonance positions, and which adjustment also selectively predetermines the broadcast frequency a gear tooth space shall represent and also selectively predetermines the broadcast frequency to be manually preselected 20 and time controlled.

The dielectric adjustable brush supports 17-18 are supported in fixed spaced relation to each other and the brushes 14-15 mounted 30 thereon are supported in fixed adjusted relation to the periphery of cylinder 12 and non-conducting space dielectric insert or single circuit breaking element 16 by means of a stationary support 19 provided with a shoulder 19a, a spacing block 19b between the rings 17-18 and a clamp block 19c, the whole adapted to be tightly clamped together by the screw 19d and thus secure the rings 17-18 and the brushes 14-15 in correct spaced and selectively predetermined adjusted relation to the dielectric insert or single circuit breaking element 16.

In Figure 2 the adjustable brush supports 17-18 are likewise supported in spaced relation in a stationary support 19, but in this instance 45 the periphery of the supports 17-18 are provided with worm gear teeth so the metal brushes 14-15 mounted on rings 17-18 may be adjusted around the periphery of cylinder 12 and relative to non-conducting space dielectric insert or single circuit breaking element 16 by means of the manually operable worm gear 20 disposed in support 19 in engagement with the gear teeth 17a of the supports 17-18. By thus manually rotating either of the rings 17-18 in either direction its 50 contact brush is adjusted to any of a multiplicity of positions around the cylinder 12 relative to the non-conducting space dielectric insert or single circuit breaking element 16 which adjustment selectively predetermines the actuation of the tuning electrodes, the circuit synchronizing position of the tuning electrodes, the opening of the motor circuit, the stopped and fastened position of the tuning electrodes and the broadcast frequency to be manually preselected for a period 60 of time. It will be apparent that while the supports 17-18 are nominally as of dielectric material they might be of metal suitably insulated from each other and from other current carrying elements.

70 The selectively operative means for manually preselecting the selectively predetermined broadcast frequencies or closing of the motor circuit and for manually preselecting the receiver "on" and "off" control, comprises a plurality of parallel spaced metal bars herein termed frequency

selecting bars, two of which bars 21-22 are shown along with a similar bar 23 herein termed a receiver control bar provided for the manual preselection of the time controlled period at which the receiver will be placed in and out of receiving condition or operation by means of suitable apparatus herein-elsewhere set forth. All of said bars 21-22-23 are mounted on a dielectric support 24.

Forty-eight parallel spaced metal bars herein 10 termed time period selecting bars are provided, of which five, 25-26-27-28-29 are shown, all of which are also mounted on the dielectric support 24 in relative spaced relation with but out of electric contact to and intersecting the frequency selecting and receiver control bars 21-22 and bar 23. These forty-eight time period selection bars represent twelve hours of time divided into forty-eight periods of fifteen minutes each, and the five time bars 25-26-27-28-29 shown represent 20 the several fifteen minute periods from ten to eleven o'clock inclusive.

The forty-eight time period bars, five of which are shown, are each provided with a series of holes equal in number to the number of frequency selecting bars plus a receiver control bar, three of said series of holes being shown in each of the said five time period bars 25 to 29 and indicated as holes 30, 31, 32, 33, 34, 35, 36, 37, 38, 39, 40, 41, 42, 43, 44, and each of said holes 30 in a time period selecting bar registering with a like hole provided in each of the underlying frequency selecting bars, as in bars 21, 22, and receiver control bar 23, and the holes in the time period selecting bars and the registering holes, 35 not shown, in the underlying bars 21, 22, 23 are adapted to receive manual selecting conductor plugs of metal, as 45, electrically connect any of the forty-eight time period selecting bars with any of the frequency selecting bars and thus 40 manually preselect any selectively predetermined broadcast frequency for any period of time, and also manually preselect the turning of the receiver on and off at the beginning and ending of any selected period of time.

A plurality of electro-magnetic current controlling relays are provided, one for each of the frequency selecting bars and the receiver control bar, three of which relays are shown, one for each of the frequency selecting bars 21-22 and 50 one for the time control bar 23. Each relay comprises electro-magnets 46-47-48 and a yielding armature 49-50-51, and each electrically connected in circuit with a frequency selecting bar 21-22 and bar 23 by conductors 46a, 47a, 55 48a, and all the yielding metal armatures 49, 50, 51 are mounted on a common electric current conducting metal support 52.

It will now be apparent that a particular frequency selecting bar, or all of any number of 60 said bars provided, may each represent some particular or preferred radio station or broadcast frequency, and it will also be apparent that such particular broadcast frequencies are each selectively predetermined by adjusting the position 65 of each of the co-acting adjustable contact brushes 14-15 around the periphery of cylinder 12 and relative to dielectric insert or single circuit breaking element 16, and it will be further apparent that the so predetermined broadcast 70 frequency of any one or more frequency selecting bars can be changed to any other broadcast frequency by selectively adjusting the position of any one or more contact brushes 14-15 relative to the dielectric insert 16, and thus the mul- 75

tiplicity of manually preselected time controlled tuning or synchronizing positions of the tuning elements 5—6 and the stopping and fastening thereof for periods of time can be selectively predetermined and altered according to expediency or preference by selectively adjusting one or

more contact brushes 14—15 relative to the single dielectric insert or single circuit breaking element 16, which adjustment effects predetermination of the opening of the motor circuit, the setting of the tuning elements 5—6 and the stopping and fastening thereof and the predetermination of the frequency to be manually preselected and time controlled.

15 The means provided for placing the radio receiver in and out of operating or receiving condition, or for turning the receiver "on" and "off" at preselected time controlled periods comprises a pair of electrically insulated resilient metal conductor strips 53—54 adapted to be actuated into and out of electrical contact by a cam wheel 55 which is step rotated by a pawl 56 cooperating with a ratchet wheel 57 on cam 55, which pawl 56 is reciprocally actuated by a like actuation of the pivoted armature 58 by the electromagnet 59 and spring 60, the armature 58 and pawl 56 being yieldingly held in the position shown by spring 60.

30 The means provided for controlling the output volume or audio tone level in conformity with the signal strength of the various broadcast frequencies comprises an arm 61 pivoted at 61a in sliding contact with a resistance unit 62 and adapted to be moved to various positions relative to the resistance unit by being reciprocated by the co-action of spring 63 and cam 64 formed out of a projecting flange on cylinder 12. The output volume may be thereby controlled either by varying the filament temperature or the grid 40 bias potential of the radio receiver through adjusting a suitable resistance 62, or by de-tuning the circuits by actuating a suitable capacity.

45 The means for time controlling the rotative and axial movement of the movable element 5 to a multiplicity of selectively predetermined frequency tuning positions at and for preselected periods of time comprises a suitable spring or electrically driven time-clock mechanism 65 adapted to bring the tip 66a of resilient material fixed to and extending from an hour driven element or arm 66 into successive electric connection with each one of the forty-eight time period bars, such as 21, 22, 23, through the successive electrical contact of said resilient tip with each 55 one of forty-eight circularly arranged and spaced metal contact pins 67 mounted in a dielectric support 68. These forty-eight pins represent the forty-eight time period bars and the dividing of twelve hours of time into forty-eight fifteen minute periods of time. Each of these forty-eight pins is electrically connected to an individual time period selecting bar, and thereby made an integral electrical conducting part of the time period selecting bars, five of these pins 67a, 67b, 67c, 67d, 67e being shown electrically connected by conductors 25a, 26a, 27a, 28a, 29a to the five time period selecting bars 25, 26, 27, 28, 29, and the said five metal pins so connected represent the several fifteen minute periods from 10 to 11 o'clock.

70 The time clock mechanism 65 is also adapted to bring a resilient tip 69a fixed to and extending from the end of a minute driven element or arm 69 into successive delayed electrical contact with one of four metal pins 70, 71, 72, 73

also mounted in an equidistantly spaced about the dielectric support 68. These four metal pins are all electrically connected to a single common conductor 74 and these four pins represent one hour of time divided into four fifteen minute periods. 5

A contact delaying boss 75 is located adjacent each of the pins 70, 71, 72, 73 the purpose of which is for the engagement and detaining or delaying the contact of the tip 69a with the pins 70 to 73 so that it will pass off a contact delaying boss 75 and snap quickly into electrical contact with each successive pin 70, 71, 72, 73 exactly at the beginning of each fifteen minute period. It will be recognized that by providing that the 15 minute arm only shall make and break the electrical circuit to the current source the period of time the electric current will flow from the source will be much shortened over the time period flow of a contact made by the hour arm, thus effecting a very considerable saving in current. 20

As has been pointed out, the broadcast frequency and opening of the motor circuit that any or all of the frequency selecting bars 21—22 represent is determined and may be changed to 25 any other broadcast frequency by a suitable adjustment of the brushes 14—15 relative to the element 16 in cylinder 12, and after suitably adjusting said brushes 14—15 so frequency selecting bars 21—22 represent, say, WJZ and WOR, the operation is as follows:

A conductor plug is inserted in, say, each of the holes 32, 35, 40, 44 in the respective time period selecting bars 25, 26, 27, 28, 29 to electrically connect the respective time period selecting bars with the frequency selecting bars 21—22 and the receiver control bar 23, and thus manually preselect the broadcast reception from, say, WJZ for the first half hour from 10 to 10:30 40 o'clock, and a succeeding half hour reception from, say, WOR from 10:30 to 11 o'clock, and thus preselectively turning on of the receiver at 10 o'clock and the turning off of the receiver at 11 o'clock. 45

Having made the foregoing manual preselections with plugs 45, and with the hour and minute arms 66—69 in the position shown, that is, at exactly the ten o'clock position, current will flow from source A along conductors 76—74 to 50 metal pin 70, contact tip 69a, arm 69, tip 66a, arm 66, pin 67a, conductor 25a to time period control bar 25, through a plug 45 in hole 40 to receiver control bar 23, along conductor 46a, through coil of magnet 46 and conductor 77 back 55 to source A. Magnet 46 thus energized attracts armature 49 into electrical contact with metal magnet core 49a whereupon current flows from source A along conductor 78, metal support 52, armature 49, core 49a, conductor 79 through coil 60 of magnet 59 and along conductor 80 back to source A; this flow of current energizes magnet 59 which actuates its armature 58 and pawl 56 to rotate the cam 55 one-eighth turn and effect the electrical contact of the conductor elements 53—54 and a flow of electric current into the receiver to place it in operating condition. Simultaneously current will also flow from the time period control bar 25 through a plug 45 in hole 35 to frequency selecting bar 22, conductor 70 47a, through coil of magnet 47 and along conductor 77 back to source A and this flow of current energizes magnet 47 which attracts its armature 50 into electrical contact with metal magnet core 50a, whereupon current flows from 75

source A along conductor 78, metal support 52, armature 50, core 50a, along conductor 81 to brush 15, through cylinder 12 to brush 13, along conductor 82, through coil of magnet 10, and 5 along conductor 77 back to source A; this flow of current energizes magnet 10 which magnetically attracts latch bar 9 disengaging it from a tooth notch in gear 3 and electrically connecting it with the member 11, whereupon current will flow from 10 source A through conductor 78, metal support 52, conductor 83, through motor 1, and through conductor 84, contact 11, latch bar 9 and conductors 85—77 back to source A; this flow of current energizes motor 1 and therethrough im- 15 parts rotation to gear 3, shaft 4, movable element 5, gear 7, cylinder 12 and cam 64, and more particularly, through the coaction of the eccentrically pivoted gear 7 imparts rotative and in cooperation with spring 8 reciprocatory axial 20 movement to the element 5 to effect the inter-engaging of its axial circular plates with like plates on element 6, and this rotative and axial movement will continue until the plates 5a, 6a of the movable and stationary elements 5—6 25 are in the correct relative position to synchronize the circuits of the radio frequency receiver with the selectively predetermined manually preselected broadcast frequency of WJZ, and at this synchronizing position dielectric insert or single 30 circuit breaking element 16 on cylinder 12 will be positioned under brush 15 and its electrical contact with cylinder 12 will be broken and the current flow through magnet coil 10 stopped thus de-energizing magnet 10 and releasing latch bar 35 9 from electrical contact with member 11 and break the electrical circuit through motor 1 and permit the latch bar 9 to engage a tooth notch in gear 3 to stop and fasten the tuning elements 5 and 6 in this particular circuit synchronizing 40 position for a manually preselected period of time. Thus the radio receiver will have been automatically turned on and connected in circuit with a source of electric energy at and for manually preselected periods of time, and the 45 radio receiving circuits automatically synchronized with a selectively predetermined manually preselected broadcast frequency at and for a pre-selected period of time.

During the interval of time from 10 to 10:30 50 o'clock while the reception of the WJZ broadcast continues, the contact tip 69a of the minute arm 69 will have passed over pin 71 and at exactly 10:30 o'clock tip 69a will snap into contact with pin 72, and the hour arm tip 66a will have 55 passed over pin 67b and at 10:30 will be in contact with pin 67c, whereupon current will again flow from source A along conductors 76—74, through tip 69a, arm 69, arm 66 and tip 66a, pin 67c, conductor 27a to time selecting bar 27, 60 through a plug 45 in hole 32 to frequency selecting bar 21, conductor 48a, through coil of magnet 48 and along conductor 77 back to source A; this flow of current energizes magnet 48 which attracts its armature 51 into electrical contact 65 with the metal magnet core 51a whereupon current flows from source A through conductor 78, metal support 52, armature 51, core 51a and along conductor 81a to brush 14, through cylinder 12 to brush 13, along conductor 82, through 70 coil of magnet 10 and along conductor 77 back to source A; this flow of current again energizes magnet 10 which attracts the latch bar 9 thereby disengaging it from a tooth notch in gear 3 and into electrical contact with member 11, 75 whereupon current will again flow from source

A through conductor 78, metal support 52, conductor 83, through motor 1, conductor 84, contact 11, latch bar 9 and conductors 85—77 back to source A; this flow of current energizes motor 1 which again imparts rotation to gear 3, shaft 4, movable element 5, gear 7, cylinder 12 and cam 64, and more particularly, through the coaction of the eccentrically pivoted gear 7 and spring 8 imparts both rotative and reciprocatory axial movement to element 5 and effects a 10 change in the interengaged position of its circular plates with the plates of element 6, and this movement to change the interengaged position of said tuning element plates will continue until the plates of movable element 5 are in correct inter- 15 engaged relation to the plates of stationary element 6 to synchronize the receiver circuits to this second selectively predetermined manually preselected broadcast frequency of WOR, and at this second synchronizing position the dielectric insert or single circuit breaking element 16 on cylinder 12 will be positioned under brush 14 and its electrical contact with cylinder 12 broken and the current flow through magnet 10 stopped thus de-energizing magnet 10 and releasing latch bar 20 25 9 from electrical contact with member 11 and breaking the electric circuit through motor 1 and permitting the latch bar 9 to engage a tooth notch in gear 3 to stop and fasten the tuning element 5 in this second particular circuit 30 synchronizing position for a preselected period of time. Thus the tuning of the receiver circuits to synchronize with the broadcast radio frequency of, say, WJZ will have been automatically changed at the preselected time of 10:30 35 broadcast radio frequency of, say WOR, at and for the succeeding manually preselected period of time.

During the interval of time from 10:30 to 11 40 o'clock while the reception of the WOR broadcast continues the tip 69a of minute arm 69 will have passed over pin 73 and exactly at 11 o'clock the tip 69a will snap into electrical contact again with pin 70 and the tip 66a of the hour arm will have passed over pin 67d and at 11 o'clock will 45 be in contact with pin 67c, whereupon current will again flow from source A along conductors 76—74 to pin 70, tip 69a, arm 69, arm 66, tip 66a, pin 67c, conductor 29a, time bar 29, through a plug 45 in hole 44 to receiver control bar 23, 50 conductor 49a, through coil of magnet 49 and conductor 77 back to source A; this flow of current energizes magnet 49 which attracts its armature 49 into electrical contact with metal magnet core 49a, whereupon current flow from source A along conductor 78, metal support 52, armature 49, core 49a, conductor 79, through coil of magnet 59 and along conductor 80 back to source A; this flow of current again energizes 55 magnet 59 which magnetically actuates its armature 58 and the connected pawl 56 to again rotate cam 55 one-eighth of a revolution and effect the electrical disconnection of elements 53—54 and discontinue the flow of electricity 60 into the receiver, and thus places the receiver out of operating condition and effects a discontinuance of broadcast radio frequency reception at 11 o'clock, or at the expiration of the preselected interval or period of time.

Manually operable electric circuit closing means is provided whereby the radio receiver control magnet 59 can be energized and the receiver turned on and off at any time independent of the preselecting and time controlling 70

means, and also whereby the release and motor circuit closing magnet 10 and the electric responsive means (motor 1) can be energized and the adjustable electrode actuated to and stopped 5 and fastened in any frequency synchronizing position at any time independent of the adjustable frequency selecting and changing means, the manual preselecting or the time controlling means, and this manual operable means for the 10 receiver control magnet 59 comprises a manually operable circuit closing device 86 connected with the source A by conductor 87 and with control magnet 59 by conductors 87a-79 and when this circuit is closed by circuit closer 86 the 15 magnet 59 is energized and actuates armature 58 and pawl 56 to intermittently rotate the cam 55 and alternately close and open the circuit of the operating current source and turn the receiver on or off.

20 This manually operable means for the releasing and motor circuit closing magnet 10 also comprises a circuit closing device 88 connected with source A by conductors 88a and 83 and with release magnet 10 by conductors 88b and 25 82. When this circuit is closed by device 88 the magnet 10 is energized and actuates latch bar 9 to release the adjustable electrode and energize motor 1 which slowly actuates the electrode 5 to any desired frequency synchronizing position, and when this circuit is opened by device 30 88 magnet 10 is de-energized, latch bar 9 is actuated to stop and fasten the electrode in such adjusted position and de-energizes motor 1 until this circuit is again closed by device 88, or until 35 the magnet 10 is energized by a current flow through the adjustable frequency selecting and changing means effected by the functioning of the preselected time controlled circuit at some preselected period of time, when the electrode 5 40 will be automatically adjusted to a selectively predetermined preselected frequency synchronizing position at and for a preselected period of time or until the devices 86 and 88 may be again actuated.

45 It will be apparent that the electromagnetic circuit closing relays 46, 47, 48 can be dispensed with and the frequency selecting bars 21-22 electrically connected directly with the adjustable brushes 14-15 through conductors 81-81a respectively and with magnet 10 through brushes 14-15, cylinder 12, brush 13 and conductor 82 to control the energization of magnet 10 and motor 1, and that the receiver control bar 23 can be electrically connected directly with the magnet 55 59 by conductor 79. With these electromagnetic relays thus dispensed with, the minute and hour actuated members of the time synchronized means will be interposed directly in the circuit between the source of current A and the magnet 10 60 and magnet 59, and will time control the energization of the magnet 10, the actuation of the latch bar 9 to unfasten the electrode 5 and energize motor 1 direct and in conformity with the manual preselections, and will also control 65 the energization of magnet 59 to turn the receiver on or off in accordance with manual preselections; and this and other variations may be made within the scope of the invention and portions may be used without others.

70 Having thus described my invention, I claim:

1. In means for effecting predetermined tuning of the receiving circuits of a radio receiver including at least one tuning element to resonance with transmitted radio frequencies, a motor connected in circuit with a source of electric energy

operatively connected with and adapted to adjust the tuning element, means connected in the motor circuit to stop and fasten the tuning element against movement in any direction from adjusted position and close and open the motor circuit and normally urged to motor circuit opening and tuning element holding position, radio frequency selecting means connected in a normally open circuit with a source of electric energy, time controlled circuit closing means connected in and adapted to close the circuit of said frequency selecting means at predetermined selected periods of time, and means connected in circuit with the frequency selecting means rendered active upon the closing of the circuit of the frequency selecting means to actuate the motor circuit closing and opening and tuning element stopping and fastening means to circuit closing and tuning element releasing position and rendered inactive upon the opening of the circuit of the frequency selecting means to permit said means to move to circuit opening and tuning element stopping and fastening position.

2. In means for effecting predetermined tuning of the circuits of a radio receiver to resonance with transmitted radio frequencies as claimed in claim 1, manually selective means to predeterminedly vary the time of closing the circuit of the frequency selecting means by the time controlled circuit closing means and periods of time 30 the frequency selecting means and tuning element actuating means are rendered active.

3. In means for effecting predetermined tuning of the circuits of a radio receiver to resonance with transmitted radio frequencies as claimed in claim 1, manually selective means to predeterminedly vary the time of closing the circuit of the frequency selecting means by the time controlled circuit closing means and periods of time 35 the frequency selecting means and tuning element actuating means are rendered active, and means connected in the circuit of the radio receiver operative from and by the adjustment of the tuning element to regulate the output of the radio receiver.

4. In means for tuning the receiving circuits of a radio receiver including at least one tuning element to resonance with transmitted radio frequencies, a motor connected in circuit with a source of electric energy operatively connected to and adapted to adjust the tuning element, a member rotatable with the tuning element, means operative in one position to engage said member to stop and fasten the tuning element against movement in any one of a plurality of tuning 55 positions and open the motor circuit and in another position unfasten the tuning element and close the motor circuit, radio frequency selecting means connected in a normally open circuit with a source of electric energy having means connected in circuit therewith rendered active upon closing the circuit thereof to actuate the means engaging the member rotatable with the tuning element out of engagement therewith to release the tuning element and close the motor circuit 60 and permit said means to engage said member and stop and fasten the tuning element and open the motor circuit when the tuning element has been adjusted to synchronize the radio receiving circuit to resonance with the selected radio frequency, time controlled circuit closing means connected in and adapted to close the circuit of the frequency selecting means at predetermined selected periods of time, and manually operated circuit closing means to render active the means 70 75

to operate the tuning element stopping and fastening means to tuning element unfastening position and to motor circuit closing position to render the motor active to adjust the tuning element 5 independent of the time controlled circuit closing means.

5. In means for effecting predetermined tuning of the receiving circuits of radio apparatus including at least one tuning element to resonance 10 with transmitted radio frequencies, circuit closing and opening means in the electrical connection of the radio apparatus with its source of electric energy, a motor connected in circuit with a source of electric energy operatively connected with the 15 tuning element to adjust the same, circuit closing and opening means in the motor circuit adapted to stop and fasten the tuning element against movement in adjusted position, frequency selecting means connected in a normally open circuit 20 with the source of electric energy, time controlled circuit closing means connected in and adapted to close the circuit of the frequency selecting means at predetermined selected periods of time, means operative upon the closing of the circuit 25 of the frequency selecting means to actuate the motor circuit closing and opening and tuning element stopping and fastening means to release the tuning element and close the motor circuit to effect actuation of the motor and adjustment 30 of the tuning element to tune the radio receiver circuit to resonance with the selected frequency, means connected in the circuit of the frequency selecting means operative when the tuning element has been adjusted to synchronize the frequency 35 of the radio receiver circuit to resonance with the selected radio frequency to open the circuits of the motor and frequency selecting means, and electromagnetic means to actuate the circuit closing means in the radio receiver circuit connected 40 with the time controlled circuit closing means and rendered active at predetermined periods of time to close and open the radio receiver circuit.

6. In means to effect predetermined tuning of 45 the receiving circuits of radio apparatus to resonance with transmitted radio frequencies, a pair of electrodes connected in the radio receiving circuits each including a disk having concentrically spaced annular plates extended from a face thereof 50 and arranged with the plates of one electrode in opposed relation to the spaces between the plates of the other electrode and one electrode being rotatable and axially adjustable relative to the other to interengage the plates of the electrodes, actuating means to rotate and impart 55 reciprocatory axial movement to the adjustable electrode, selectively settable means adapted to effect adjustment of the adjustable electrode by its actuating means to predetermined positions 60 relative to the fixed electrode and tune the radio receiving circuit of the radio apparatus into resonance with selected radio frequencies, and time controlled means to close the power circuit of the radio apparatus and effect operation of the 65 adjustable electrode actuating means and adjustment of said electrode to tune the receiving circuit of the radio apparatus into resonance with selected radio frequencies at predetermined periods of time and open the radio receiving circuit 70 after a selected predetermined period of time.

7. In means to tune the receiving circuits of radio apparatus to resonance with transmitted radio frequencies, a pair of cup electrodes connected in the circuit of the radio apparatus, one 75 electrode being fixed and the other electrode sup-

ported to be rotated and have reciprocatory axial movement to variably adjust said electrode relative to the fixed electrode, a motor connected in a normally open circuit with a source of electric energy having a gear on the shaft thereof meshing with a driven gear rotatable with and to transmit rotary movement to the adjustable electrode, means to effect reciprocatory axial movement of the adjustable electrode and adjustment thereof relative to the fixed electrode, means constituting a circuit closer connected in the circuit of the motor normally urged to circuit opening position and into engagement with a tooth space of the driven gear to retain the electrode in adjusted position, an electromagnet adapted when energized to release said means from the driven wheel and close the circuit of the motor, a metallic cylinder actuated co-ordinately with the adjustable electrode and having a dielectric insert arranged in the peripheral wall, a contact maker 10 in electrical connection with the electromagnet contacting with said cylinder, frequency selecting means connected with the electromagnet in open circuit with the source of electric energy including contact makers adapted to contact with the 15 cylinder in predetermined stepped relation about the cylinder and close the circuit of the electromagnet through one of said contact makers and energize the electromagnet to actuate the electrode retaining means to releasing position and 20 close the motor circuit and effect adjustment of the electrode and by contact of said contact maker with the dielectric cylinder insert open the circuit of and de-energize the electromagnet and permit the motor circuit closing and electrode retaining means to assume electrode retaining position and open the motor, time controlled circuit closing means connected in the circuit of the frequency selecting means and adapted to close said circuit through a predetermined stepped contact 25 maker and effect selected adjustment of the adjustable electrode at predetermined periods of time.

8. In means to tune the receiving circuits of radio apparatus to resonance with transmitted 45 radio frequencies, a pair of cup electrodes connected in the circuit of the radio apparatus, one electrode being fixed and the other electrode supported to be rotated and have reciprocatory axial movement to variably adjust said electrode relative to the fixed electrode, a motor connected in a normally open circuit with a source of electric energy, said motor having a gear on the shaft thereof meshing with a driven gear rotatable with and to transmit rotary movement to the adjustable electrode, means to effect reciprocatory axial adjustment of the adjustable electrode relative to the fixed electrode, a circuit closer connected in the circuit of the motor normally urged to circuit opening position and into engagement 50 with a tooth space of the driven gear to retain the electrode in adjusted position, an electromagnet adapted when energized to release the circuit closer from the drive wheel and close the circuit of the motor, a metallic cylinder actuated co-ordinately with the adjustable electrode and having a dielectric insert arranged in the peripheral wall, a contact maker in electrical connection with the electromagnet contacting with said cylinder, frequency selecting means connected 55 with the electromagnet in open circuit with the source of electric energy including contact makers adapted to contact with the cylinder in predetermined stepped relation about the cylinder and adapted to close the circuit of the electro- 60

70

75

magnet through one of said contact makers and cylinder and open the circuit by contact of said contact maker with the dielectric cylinder insert, and time controlled means to close the circuit of the frequency selecting means through a predetermined stepped contact maker and thereby effect a selected adjustment of the adjustable electrode at predetermined periods of time.

9. In means to tune the receiving circuits of radio apparatus to resonance with transmitted radio frequencies, a pair of cup electrodes connected in the circuit of the radio apparatus, one electrode being fixed and the other electrode supported to be rotated and have reciprocatory axial movement to variably adjust said electrode relative to the fixed electrode, a motor connected in a normally open circuit with a source of electric energy having a gear on the shaft thereof meshing a driven gear rotatable with and to transmit rotary movement to the adjustable electrode, means to effect reciprocatory axial adjustment of the adjustable electrode relative to the fixed electrode, a circuit closer connected in the circuit of the motor normally urged to circuit opening position and into engagement with a tooth space of the driven gear to retain the electrode in adjusted position, an electromagnet adapted when energized to release the circuit closer from the driven wheel and close the circuit of the motor, a metallic cylinder actuated co-ordinately with the adjustable electrode and having a dielectric insert arranged in the peripheral wall, a contact maker in electrical connection with the electromagnet contacting with said cylinder, frequency selecting means connected with the electromagnet in open circuit with the source of electric energy including contact makers to contact with the cylinder in predetermined stepped relation about the cylinder to close the circuit of the electromagnet through one of said contact makers and open the circuit by contacting said contact maker with the dielectric cylinder insert, adjustable supports for said stepped contact makers to variably adjust the contact makers about the cylinder, time controlled means to close the circuit of the frequency selecting means and electromagnet through a predetermined stepped contact maker to energize the electromagnet and close the motor circuit and effect predetermined adjustment of the adjustable electrode and maintain said adjustment for a predetermined period of time, and selective means interposed in the circuit of the time controlled means with the frequency selecting means to vary the period of time of closing the circuit of the frequency selecting means and vary the time of maintaining an adjustment of the adjustable electrode and effecting a further predetermined adjustment of the same.

10. In means to tune the receiving circuits of radio apparatus to resonance with transmitted radio frequencies as claimed in claim 8, wherein the electrodes each embody a disk having concentrically spaced plates extended from a face thereof with the plates of one electrode arranged in opposed relation to the spaces between the plates of the other electrode, and the means to impart reciprocatory axial movement to the adjustable electrode comprises an eccentrically supported gear meshing with a gear rotatable co-ordinately with the adjustable electrode to transmit axial movement to the electrode in one direction, and a spring co-acting with said eccentric gear to transmit axial movement to the electrode in the opposite direction.

11. Means to tune the receiving circuits of radio apparatus to resonance with transmitted radio frequencies as claimed in claim 8, wherein the circuit closer connected in the motor circuit and engaging a tooth space of the driven gear to hold the adjustable electrode against movement, comprises a pivoted detent pawl connected with the source of electric energy, a spring to urge the pawl into engagement with a tooth space of the driven gear, and the energizing of the electromagnet in circuit with the frequency selecting means attracting said pawl out of engagement with the tooth space of said gear and a contact terminal actuated by said pawl into electrical contact with a contact terminal connected in the motor circuit to close the circuit of the motor with the source of electric energy.

12. Means to tune the receiving circuits of radio apparatus to resonance with transmitted radio frequencies as claimed in claim 8, wherein the circuit closer connected in the motor circuit and engaging a tooth space of the driven gear to hold the adjustable electrode against movement, comprises a pivoted detent pawl connected with the source of electric energy, a spring to urge the pawl into engagement with a tooth space of the driven gear, and the energizing of the electromagnet in circuit with the frequency selecting means attracting said pawl out of engagement with the tooth space of said gear and a contact terminal actuated by said pawl into electrical contact with a contact terminal connected in the motor circuit to close the circuit of the motor with the source of electric energy.

13. In means to tune the receiving circuits of radio receiving apparatus including at least one tuning element to resonance with radio frequencies, a motor adapted to adjust the tuning element connected in circuit with a source of electric energy, a circuit closer in the motor circuit normally urged to circuit opening position, means to operate said circuit closer and stop and fasten the tuning element in adjusted position against movement in any direction and normally urged to tuning element stopping and fastening position, frequency selecting means connected in open circuit with a source of electric energy comprising a single conductor member arranged with a circuit breaking element and actuated co-ordinately with the tuning element, and a plurality of contact makers in contact with and adjustable on said conductor member relative to the circuit

nected with the electromagnet in open circuit with the source of electric energy including contact makers to contact with the cylinder in predetermined stepped relation about the cylinder to close the circuit of the electromagnet through one of said contact makers and open the circuit by contacting said contact maker with the dielectric cylinder insert, adjustable supports for said stepped contact makers to variably adjust the contact makers about the cylinder, time controlled means to close the circuit of the frequency selecting means and electromagnet through a predetermined stepped contact maker to energize the electromagnet and close the motor circuit and effect predetermined adjustment of the adjustable electrode and maintain said adjustment for a predetermined period of time, and selective means interposed in the circuit of the time controlled means with the frequency selecting means to vary the period of time of closing the circuit of the frequency selecting means and vary the time of maintaining an adjustment of the adjustable electrode and effecting a further predetermined adjustment of the same.

14. Means to tune the receiving circuits of radio apparatus to resonance with transmitted radio frequencies as claimed in claim 8, wherein the electrodes each embody a disk having concentrically spaced plates extended from a face thereof with the plates of one electrode arranged in opposed relation to the spaces between the plates of the other electrode, and the means to impart reciprocatory axial movement to the adjustable electrode comprises an eccentrically supported gear meshing with a gear rotatable co-ordinately with the adjustable electrode to transmit axial movement to the electrode in one direction, and a spring co-acting with said eccentric gear to transmit axial movement to the electrode in the opposite direction.

15. Means to tune the receiving circuits of radio apparatus to resonance with transmitted radio frequencies as claimed in claim 8, wherein the circuit closer connected in the motor circuit and engaging a tooth space of the driven gear to hold the adjustable electrode against movement, comprises a pivoted detent pawl connected with the source of electric energy, a spring to urge the pawl into engagement with a tooth space of the driven gear, and the energizing of the electromagnet in circuit with the frequency selecting means attracting said pawl out of engagement with the tooth space of said gear and a contact terminal actuated by said pawl into electrical contact with a contact terminal connected in the motor circuit to close the circuit of the motor with the source of electric energy.

16. In means to tune the receiving circuits of radio receiving apparatus including at least one tuning element to resonance with radio frequencies, a motor adapted to adjust the tuning element connected in circuit with a source of electric energy, a circuit closer in the motor circuit normally urged to circuit opening position, means to operate said circuit closer and stop and fasten the tuning element in adjusted position against movement in any direction and normally urged to tuning element stopping and fastening position, frequency selecting means connected in open circuit with a source of electric energy comprising a single conductor member arranged with a circuit breaking element and actuated co-ordinately with the tuning element, and a plurality of contact makers in contact with and adjustable on said conductor member relative to the circuit

- breaking element and the circuit breaking element being common to all of the contact makers, selectively operable means to close the circuit of the frequency selecting means through any one 5 of said contact makers and the conductor member and said circuit adapted to be opened by the contact maker through which the circuit is closed contacting the circuit breaking element, magnetic means connected in circuit with the frequency 10 selecting means rendered active upon the closing of a circuit through any one of said contact makers and the conductor member by the selectively operable means to actuate the tuning element stopping and fastening means to close 15 the motor circuit, and said magnetic means rendered inactive to permit said circuit closer to assume its circuit opening position and the fastening means to assume its tuning element stopping and fastening position when the circuit of 20 the frequency selecting means is opened by the contact maker through which the circuit is closed contacting the circuit breaking element.
14. Means to tune the receiving circuits of radio apparatus to resonance with transmitted frequencies as claimed in claim 13, wherein the frequency selecting means comprises a single electric conductor member arranged with a single circuit 25 breaking element and actuated co-ordinately with the tuning element and electric contact makers 30 adapted to contact with said conductor member and adjustable relative to the circuit breaking element, a series of electric conducting members in electric connection with the contact makers and one of said members in electrical connection 35 with a circuit closer in the power circuit of the radio apparatus, a second series of electric conducting members disposed non-conductively adjacent the first series of conducting members and each of said members adapted to be periodically 40 electrically connected with the source of electric energy through a circuit closing element of the time controlled circuit closing means, and manually adjustable means to selectively electrically connect and vary the connection of one series of 45 conducting members with the other series of conducting members to effect tuning of the circuit of the radio receiving apparatus to resonance with different radio frequencies and actuation of the power circuit closer at different predetermined 50 periods of time.
15. Means to tune the receiving circuits of radio apparatus to resonance with transmitted frequencies as claimed in claim 13, wherein the frequency selecting means comprises a single electric conductor member actuated co-ordinately with the adjustable tuning element and arranged with a single circuit breaking element and electric contact makers contacting with said conducting member and adjustable relative to the single circuit 55 breaking element, a series of electric conducting members in electric connection with the contact makers and one of said members in electric connection with a controlling device in the radio receiver power circuit, a second series of electric 60 conducting members disposed non-conductively adjacent the first series of conducting members in electrical connection with the contact makers and the conducting member connected with the power circuit controlling device and each connectable with the source of electric energy through the time controlled circuit closing means to effect 65 tuning of the circuits of the radio receiving apparatus to resonance with different radio frequencies and actuate the power circuit controlling 70 device to turn the radio receiver power circuit on and off at predetermined periods of time.
16. In means to tune the receiving circuits of radio apparatus to resonance with transmitted radio frequencies as claimed in claim 13, wherein the frequency selecting means has associated therewith means to preselect periods of time comprising a series of conductor bars, each representative of a predetermined frequency and period of time and each electrically connected with the time controlled circuit closing means, and manually selective means to change the connection of said conductor bars with the time controlled circuit closing means to change the periods of time to close the circuit of the frequency 15 selecting means and tuning of the radio receiving circuit and periods of time of closing and opening the circuit of the radio apparatus.
17. Means to tune the receiving circuits of radio apparatus to resonance with transmitted frequencies as claimed in claim 13, wherein the frequency selecting means comprises a single electric conducting member arranged with a single circuit breaking element and operative co-ordinately with the adjustable tuning element, co-acting electric contact makers contacting with said conducting member and adjustable relative to the circuit breaking element, a series of perforated members each in electric connection with a contact maker and each representative of a frequency predetermined by the adjustment of its associated contact maker, a second series of perforated conductor members extending transversely of and out of electric contact with the first series of conductor members and with the perforations in register with the perforations in the first series of conductor members and each representing a period of time and connectable with a circuit closing member of the time controlled circuit closing means, and conductor members adapted to be 40 plugged into said registered perforations to predeterminedly electrically connect the conductor members and thereby the frequency selecting means with the time controlled circuit closing means.
18. In means to tune the receiving circuits of radio apparatus to resonance with transmitted radio frequencies, a pair of electrodes connected in the circuits of the radio receiver, one of which electrodes is fixed and the other adjustable relative thereto to tune the radio receiving circuits to resonance with different radio frequencies, a motor connected in a normally open circuit with a source of electric energy adapted to adjust the adjustable electrode relative to the fixed electrode, 55 means to close the motor circuit and stop and fasten the adjustable electrode against movement in adjusted position, radio frequency selecting means connected in a normally open circuit with the source of electric energy and having means 60 connected in circuit therewith rendered active upon the closing of the circuit of the frequency selecting means to actuate the electrode stopping and fastening means out of electrode fastening position and close the motor circuit and open the motor circuit and permit the electrode stopping and fastening means to assume electrode stopping and fastening position after the adjustable electrode has been adjusted to synchronize the radio receiving circuit to resonance with the selected frequency, and time controlled circuit closing means connected in and adapted to close and open the circuit of said frequency selecting means and effect adjustment of the adjustable electrode at predetermined periods of time.

19. In means to tune the receiving circuits of radio apparatus to resonance with transmitted radio frequencies as claimed in claim 17, and means connected in the receiving circuit of the 5 radio apparatus controlled from and by the adjustment of the adjustable electrode to control the audio output in accordance with the synchronized radio frequencies, comprising a resistance element connected in the receiving circuit, a pivoted conductor connected in the receiving circuit in contact with and movable relative to said resistance element to vary the current supply to elements of the radio receiving apparatus, a cam participating in the rotation and axial adjustment of the adjustable electrode cooperating with 10 said electrode to variably adjust the same to connect in or cut out of the radio receiving circuit variable amounts of the resistance element.

20. In a radio signal receiving system having at 20 least one tuning element, a motor operatively connected with the tuning element connected in circuit with a source of electricity and having a circuit closer interposed in the circuit thereof normally urged to circuit opening position, frequency selecting means connected in open circuit with a source of electricity comprising a conductor member operative co-ordinately with the tuning element and having a dielectric insert and a series of contact makers to contact with the 25 conductor member in stepped relation to the dielectric insert and to have adjustment relative to each other and the dielectric insert, selectively operative means to close the circuit of the frequency selecting means through any one of said 30 contact makers and the conductor member and said circuit adapted to be opened by the contact maker through which the circuit is closed contacting the dielectric insert, said selectively operative means including resilient electrically connected hour and minute actuated members of 35 electric conducting material, a series of insulated conductor members selectively connectable in circuit with the contact makers of the frequency selecting means and with which conductor members the hour actuated member is adapted to successively contact, a second series of conductor members connected with a source of electric energy and with which conductor members the minute actuated member is adapted to successively contact, and means to momentarily delay the contacting of the minute actuated member with said latter conducting members, and electromagnetically operated means connected in circuit with the conductor member and contact 50 makers of the frequency selecting means rendered active to actuate the circuit closer to close the motor circuit upon the closing of a circuit through any one of said contact makers and the conductor member of the frequency selecting means by the 55 selectively operative means, and said electromagnetically operated means rendered inactive to permit said circuit closer to assume its circuit opening position when the circuit of the frequency selecting means is opened by the contact maker through which the circuit is closed contacting the dielectric insert.

21. In a radio signal receiving system having at least one tuning element, electromagnetically actuated means operatively connected with the 70 tuning element and connected in a normally open circuit with a source of electricity, a conductor member operative co-ordinately with the tuning element and arranged with a circuit breaking element, a series of contact makers contacting 75 with said conductor member in stepped relation

to each other and the circuit breaking element, and selectively operative means to close the motor circuit through either one of said contact makers and conductor member, and said circuit adapted to be opened by the contact maker through which 5 the circuit is closed contacting with the circuit breaking element of the conductor member, said selectively operative means including time controlled means comprising a clock driven mechanism having electrically connected hour and minute actuated members of conducting material having a contact making tip of resilient material fixed to and extending therefrom, a circular row of insulated conductor pins electrically connected with the frequency selecting means and with 10 which pins the resilient tip of the hour actuated member is adapted to contact, a second series of pins with which the resilient tip of the minute actuated member is adapted to contact, and abutments adjacent the second series of pins for engagement of the resilient tip of the minute actuated member to effect a flexing and quick release and contacting of said tip with the pins.

22. In a radio signal receiving system having at least one tuning element, a motor to adjust the 25 tuning element connected in a normally open circuit with a source of electricity, means to stop and fasten the tuning element against movement in any direction from adjusted position, means including a conductor member arranged with a circuit breaking element and a plurality of contacts contacting the conductor member connected in a local circuit to control the closing of the motor circuit and releasing of the stopping and fastening means from the tuning element and determine 30 the operation of the motor and adjustment of the tuning element, settable time controlled means to close and include a desired one of said contacts in an operating circuit and render means active to actuate the tuning element stopping and 35 fastening means to unfasten the tuning element and close the motor circuit, effect predetermined operation of the motor and adjustment of the tuning element, and after said predetermined operation of the motor open the motor circuit 40 and permit the tuning element stopping and fastening means to assume tuning element stopping and fastening position and after a predetermined period of time open the radio receiver circuit, and said time controlled means including means 45 for the momentary delay of each periodic circuit closing means manually operable at will independently of the time controlled means to close an electric circuit to render the actuating means for the stopping and fastening means active to 50 actuate said means to unfasten the tuning element and close the motor circuit and operation of the motor and adjustment of the tuning element to non-predetermined positions and close the radio receiver power circuit, and means operative at 55 will to actuate the circuit closer of the power circuit of the radio receiver to open and close said power circuit at non-predetermined periods of time.

23. In means to tune the receiving circuits of 65 radio apparatus, including at least one tuning element, to synchronism with radio frequencies, an electric motor connected in a normally open circuit with a source of electric energy and connected with and operative to adjust the tuning 70 element, means to stop and fasten the tuning element against movement in adjusted position and to control the motor circuit normally urged to tuning element stopping and fastening position and motor circuit opening position, frequency 75

- selecting means connected in a normally open circuit with a source of electric energy including a conductor member operative co-ordinately with the tuning element and having a single non-conducting space and a plurality of contacts contacting said conductor member in stepped relation to each other and the non-conducting space, and said non-conducting space being common to all of the contacts, and means connected in circuit with the frequency selecting means operative upon the closing of a circuit through a desired one of the contacts of the frequency selecting means to release the stopping and fastening means from the tuning element and close the motor circuit and effect operation of the motor to adjust the tuning element, and said means rendered inactive to permit said locking means to assume position to stop and fasten the tuning element against movement and open the motor circuit when the contact through which the circuit is closed contacts the non-conducting space of the conductor member. 10

MERION J. HUGGINS.
